UNITED STATES PATENT OFFICE.

JOSEPH GRASSO, OF PHILADELPHIA, PENNSYLVANIA.

BUILDING CONSTRUCTION.

1,408,287.

Specification of Letters Patent. Patented Feb. 28, 1922.

Application filed March 16, 1920. Serial No. 366,190.

To all whom it may concern:

Be it known that I, JOSEPH GRASSO, a citizen of the United States, residing at Philadelphia, in the county of Philadelphia and 5 State of Pennsylvania, have invented new and useful Improvements in Building Constructions, of which the following is a specification.

The invention relates to masonry and concrete structures and more particularly to 10 building blocks and constructions for forming and building the same and it has for an object to provide a building block which can be readily interfitted with other similar 15 building blocks to form a strong and durable structure and also provide for ventilation and air space, presenting also a neat and effective appearance on the exterior.

Among other features the invention comprehends a building block or blocks which 20 are formed so that they will readily interfit, thus providing for the ready construction of a wall, column or other structure from blocks which can be quickly and cheaply 25 manufactured and may in fact be kept in stock, the relative interfitting of the blocks providing for each of them to be substantially similar, thus enabling a large number 30 of blocks to be made from a single mold. Still further the invention comprehends a building block which is of a tongue or rib and groove construction, provided also with 35 openings which when the blocks are assembled and interfitted, will bring about the provision of an air space in the wall of a 40 building or structure, whereby warm or cold air can be carried through the wall for the purpose of heating or cooling the room or chamber, formed by a number of the walls, also maintaining a building so constructed, in a dry and healthy condition.

Still further the invention comprehends various improvements in building constructions over what is shown in United States 45 Letters Patent numbered 1087011, "Building construction" granted to me February 10, 1914.

In the further disclosure of the invention, reference is to be had to the accompanying 50 drawings, constituting a part of this specification, in which similar characters of reference denote corresponding parts in all the views, and in which,—

Figure 1— is a fragmentary elevation of a 55 wall formed of my building blocks, showing the manner of providing for an air space,

part of the wall being shown in elevation and part in vertical section.

Figure 2— is a view looking down on the structure disclosed in Figure 1. 60

Figure 3— is a perspective view of one of the forms of building blocks.

Figure 4— is an end view thereof.

Figure 5— is a horizontal sectional view taken through the form of building block 65 shown in Figures 3, 4.

Figure 6— is a perspective view of a slab construction of block.

Figure 7— is an end view thereof.

Figure 8— is a plan view. 70

Referring to the views, and more particularly to Figures 1-8 inclusive, I provide a building block A, consisting of a body 10 which may be suitably molded in concrete or any other convenient material and which 75 when molded as shown in Figure 3, provides a block having vertical openings 11, formed therein, and portions 12 bordered along the upper edges by upstanding longitudinally extending ribs or tongues 13, these ribs or 80 tongues extending downwardly along one end of the block as at 14 and terminating at the other end of the block in vertical grooves 15 with the undersides of the body also 85 formed with grooves 16 extending longitudinally and in which the lower ends of the ribs 14 terminate, as shown. The block may in fact be stated to consist of three longitudinal sections 17 with each section having 90 one of the upstanding longitudinally extending ribs 13 and one of the vertical projecting ribs 14 at one end and one of the grooves 15 at the other end with one of the grooves 16 formed in the underside. These 95 sections 17 are of course molded integrally with the portions 12 which have the openings 11 therein, so that the portions 12 in fact form cross pieces or portions 18. Some of these portions may be formed with horizontal cuts or grooves 19 provided for receiving a wire or reinforcing cable or element 20 which may also be in the nature of a rod so that blocks adjacently arranged in a horizontal line will have the cuts or 100 grooves 19 aligning, whereby the insertion and disposition of the wire or rod 20 will tend to act as a connection between the adjacent blocks, aiding materially in strengthening the wall or structure that is to be formed.

As shown in Figures 1, 2, the blocks when arranged to form a wall are preferably em- 110

ployed in connection with slabs 21 which are merely another form of block and which are shown in detail in Figures 6, 7, 8, each slab consisting of a body 22 formed with 5 portions 23 providing the outer faces and an interposed portion 24 having an upstanding horizontal rib 25, an end projecting rib 26 extending vertically and forming a continuation of the rib 25 with the other end of 10 the block formed with a vertical groove as at 27 and the underside also formed with a groove as at 28 with the vertical rib 26 terminating in the groove 28 and the horizontal rib 25 terminating in the groove 27. Now 15 in building a wall, the blocks and slabs are assembled to provide a substantially vertical pillar of the blocks and then several vertical columns of the slabs. Certain of the blocks A, have the cross pieces or portions 20 18 extending throughout the vertical distance of the blocks, whereas in others these vertical cross pieces are cut off near the bottom to form openings or channels 29 and with this arrangement it will be clearly seen 25 in Figure 1, that a circulation of air between the walls of the slabs and blocks is provided in the construction of a wall such as shown and that the air which is circulated through the channels and spaces pro- 30 vided by the blocks and slabs and the relative arrangement thereof, may be a cold air or a warm air, as desired. It will be seen that the slabs are preferably arranged in three rows as shown in Figure 2, and that 35 the flange of one slab engages in the groove of the next adjacent slab or in the end vertical groove of the block and so on. This disposition of the slabs and blocks provides two vertical spaces 30, 31, one of which, 40 namely the space 31, may be reinforced by suitable reinforcing rods 32 disposed in the space 31 which is then filled in with concrete 33.

From the foregoing and the views, it will 45 be seen that a strong and durable wall is provided, the nature of which depends entirely upon the construction and arrangement of the blocks and slabs and it will be of course apparent that any number of the 50 columns and blocks can be used in connection with the slabs and that in one column of the blocks as shown in Figure 1, the channels will be near the bottom of the wall, whereas in the next column they will 55 be near the top of the wall, these channels connecting the intermediate spaces formed by the slabs.

From the foregoing, it will be apparent 60 that various adaptations of the form of building block shown can be had by reason of the novel manner of interfitting the blocks and also the slabs and that with the provision of blocks and slabs such as set out 65 a wall can be readily constructed which will present a neat and effective appearance and

which will be provided with air spaces in one part and have the other part amply reinforced by reinforced concrete construction.

It should be clearly understood that with 70 the forms of block construction shown and clearly described, I aim not only to provide a construction which when completed will be of a monolithic nature but which in the very beginning, works a saving of time, labor and material. To this end it should be noted that the individual blocks when set up are in fact forms for the subsequent filling of concrete or other reinforcement whereby the monolithic construction is obtained 75 and that these forms instead of being ultimately torn away and removed as in the nature of removable forms now generally used in concrete constructions, are in fact and become a unitary part of the 80 finished construction. It is well known that in the present construction of concrete walls for buildings and the like, the usual method adopted is to set up certain forms made either of wood or steel and then fill in between the sides of the forms, ultimately removing the forms to expose the built up structure. By careful reference to the views it will be seen that the blocks employed in the present instance after being set up are 85 filled in with concrete reinforced with suitable steel and that the blocks although primarily forming a frame-work, on the finished construction remain and become an integral part of the entire wall or other 90 structure that is being built. With this in mind it will be apparent that the facings of the blocks can be of any desired configuration or present any desired form of finish, whereas in concrete work built up with 95 forms the finish when the concrete is removed is a plain and rough one which must later on be coated or otherwise operated upon to bring about that desired monolithic appearance as for instance in the 100 making of a stucco. So also in concrete work built from forms, if a finished stone appearance or veneer appearance is desired, the same must be built on to the finished 105 construction and involves an additional 110 operation. With my form of construction there is provided a means insuring equally as much strength and durability and providing for a finish or surface which is a primary part of the operation and not a secondary additional operation involving considerable cost and expense.

Having described my invention, I claim—

1. In a building construction, vertically disposed spaced pillars consisting of blocks 125 in offset relation, transversely arranged air passages therein, the air passages of one pillar being located at a different elevation from those of the adjacent pillar, slabs connecting the pillars, said slabs being arranged 130

in vertical spaced relation to provide a space between the pillars which communicates with the air passages and thus define vertical air chambers and horizontal passages connecting the air chambers, with the air passages disposed in vertical staggered relation and means for connecting the pillars and the slabs. 15

2. In a building construction, vertically disposed spaced pillars consisting of blocks arranged in offset relation, a transversely arranged air passage therein, the air passage of one pillar being located at a different elevation from those of the adjacent pillar, slabs connecting the pillars, said slabs being arranged in vertical spaced relation to provide spaces between the pillars which communicate with the air passages and define vertical air chambers and horizontal passages connecting the air chambers with 20 the air passages disposed in vertical staggered relation and means including reinforced concrete construction for connecting the pillars and slabs. 25

In testimony whereof I affix my signature. JOSEPH GRASSO.
